UNITED STATES PATENT OFFICE.

SYLVESTER W. GIBBS, OF CANTON, OHIO.

EMBROIDERY-FRAME.

No. 929,583.

Specification of Letters Patent.

Patented July 27, 1909.

Application filed March 16, 1909. Serial No. 483,716.

To all whom it may concern:

Be it known that I, SYLVESTER W. GIBBS, a citizen of the United States, residing at Canton, in the county of Stark and State of Ohio, have invented a new and useful Improvement in Embroidery-Frames, of which the following is a specification.

The invention relates to a frame composed of an inner hoop and an outer ring, collectively known as an embroidery hoop, arranged to stretch and hold a fabric over the inner hoop for the purpose of embroidering the fabric. In frames of this character, difficulty has been experienced in constructing and arranging the parts so that the fabric can first be properly adjusted and stretched to an even and uniform tension over the inner hoop, and then tautly clamped and positively held in this relation. Further difficulty has been found in providing a frame adapted to accomplish these results with respect to fabrics of different thickness, and especially with respect to the thinner and more delicate fabrics which are likely to have their threads pulled or torn by the clamping action which is usually required for the thicker and coarser fabrics.

The invention relates to the use of a curved elastic wire for the clamping ring, hereinafter referred to as the ring, and of thin metal for the inner hoop, hereinafter referred to as the hoop; and the objects of these features of the improvement are to provide a clamping ring which can be readily adjusted to meet all the varying requirements of use, and will at the same time permit fabrics of different thickness to be readily stretched and adjusted and then positively clamped without injury thereto, and furthermore to provide a thin metal hoop shaped to furnish sufficient strength without any exposed edges to cut the fabric, and also to make an improved joint for the hoop without overlapping ends and without the use of solder.

Further purposes of the invention pertain to the shape of the hoop, which is provided with a V-shape groove in its outer face, against the sides of which the ring readily finds two separate and distinct zones of contact for clamping the intervening fabric; and also to the use of a resilient frictional material in the bottom of the groove, against which the fabric is compressed by the ring before the same is clamped against the sides of the groove.

The purposes of the invention, thus set

forth in general terms, and other ancillary advantages, are attained by the preferred embodiment of the same illustrated in several modified forms, in the accompanying drawing, forming part hereof, in which—

Figure 1 is a perspective view of the improved hoop; Fig. 2, a detached plan view of the clamping ring; Fig. 3, a fragmentary plan section showing the hoop and the ring with an intervening fabric, and the details of the clamping lever; Fig. 4, an enlarged fragmentary section of the hoop and the ring, with an intervening fabric, showing the position of the parts before the ring is clamped; Fig. 5, a similar view with a two ply hoop illustrating the joint and showing the ring clamped; Fig. 6, a view like Fig. 4, with a modified form of the hoop and; Fig. 7, a view like Fig. 5, with a modified form of hoop.

Similar numerals refer to similar parts throughout the drawing.

The hoop 1 is preferably made of sheet metal or other suitable thin material and is formed with the bead 2 on each edge thereof. In the simpler form of the hoop illustrated in Figs. 1, 2 and 4, the body or web 3 of the hoop is formed with a V-shaped groove in its outer face. The sides of the groove are convergently inclined to the plane of the hoop and the walls thereof may be of single thickness as shown in Fig. 4, or of double thickness as shown at 3^a in Fig. 5, in which latter case the flanges forming the bead are extended to the bottom of the groove, while in the former case the bead flanges are deflected inward to prevent a cutting of the fabric.

The joint for the ends of the strip out of which the hoop is formed, is made by inserting sections of wire 4 in the hollows of the beads, and then clamping the beads around the wires whereby a secure joint is obtained, as shown in Figs. 5 and 7. The clamping action of the beads on the wires is preferably supplemented by using straight sections of spring wire, which must necessarily be flexed to the curve of the beads, and the elastic tendency of the wires to straighten serves to increase the binding action of the joint. The bottom of the groove is preferably filled with some suitable resilient frictional material 5 as of rubber or leather, for the purposes hereinafter mentioned.

In the modified form of hoop shown in Fig. 6, the web 3^b is shaped to form the re-

cessed channel 6 in the bottom of the groove, in which channel the resilient frictional material 5^a is embedded; and the shoulders 7 formed by the sides of the channel, serve 5 to prevent the material from being displaced therefrom. In Fig. 7, a similar form of hoop is shown with the web 3^c made of double thickness in a manner similar to the web shown in Fig. 5.

10 The clamping ring 8 is preferably made of round resilient wire and is divided or open on one side, and the free ends are preferably bent to form the round eyes 9. The ring is preferably made so that the free ends will 15 normally overlap each other, as shown by full lines in Fig. 2, to form a circle somewhat less than that of the bottom of the groove in the hoop, so that when the ring is opened or expanded as shown by broken lines in 20 the same figure, to pass over the beaded edges of the hoop, and then contracts in the groove of the hoop, there will yet remain sufficient energy in the spring of the ring to compress the fabric 10 with some degree of 25 firmness against the resilient frictional material in the bottom of the groove, as shown in Figs. 4 and 6, but at the same time permits the fabric to be drawn one way or another to be properly adjusted and stretched 30 on the hoop. In this relation of the parts, the ring and the hoop are preferably so shaped that there will be no clamping of the fabric between the ring and the sides of the groove in the hoop.

35 The clamping lever is preferably formed U-shaped with the side plates or arms 11 joined at one end by the yoke 12, in which yoke is provided the adjusting screw 13. The lever is hinged by its arms to one end 40 of the ring, preferably by means of the pivot 14 passed through the eyes of the ring, and the inner end of the screw is adapted, by a proper adjustment of the screw, to engage the farther side of the eye on the other end 45 of the ring, which eye acts as a cam to draw and clamp the ends of the ring toward each other, as shown in Fig. 2. The outer end of the screw is preferably provided with the knurled spherical head 15, by means of 50 which the screw is readily adjusted by the thumb and finger. It is evident that by shaping the cam so that the screw will pass beyond a dead center, as shown in Fig. 3, the ring can be locked in its clamped position and will not be loosened by the ordinary use of the frame.

The parts are so proportioned and arranged 55 that after the ring has been placed in position around the hoop and the intervening fabric 10, as shown in Figs. 4 and 6, a further contraction of the ring by the closing of the lever, serves to clamp the fabric between the ring and the hoop along two zones of contact against the opposite walls of the groove, 60 which positive clamping action is permitted

by a compression of the resilient frictional material in the bottom of the groove, as shown, and the wedging of the round-wire ring between the converging sides of the groove.

70 It will be understood that the use of the resilient frictional material in the bottom of the groove is not essential to the other features of the invention and that the same can be dispensed with when the thicker fabrics are used in the frame, in which event the elasticity of the ring compresses the fabric against the sides of the hoop groove with sufficient force to hold the fabric while it is being adjusted and stretched in proper position; but the use of the resilient frictional material is preferred for holding the thinner fabrics in the frame. It is furthermore evident that very fine and delicate fabrics can be held in the frame with sufficient firmness by adjusting the ring to compress the fabric against the resilient frictional material without much, if any, clamping of the fabric between the ring and the sides of the hoop groove. And finally, it will be understood 80 that the use of sheet metal for the hoop is not essential to the other features of the invention, although such material is preferred for conveniently shaping the beads and the web portions thereof.

95 What I claim as my invention, and desire to secure by Letters Patent, is—

1. An embroidery frame including a hoop having a V-shaped groove in its outer face with a recessed channel in the bottom of the groove and a resilient frictional material in the channel, in combination with an elastic ring adapted to compress the resilient frictional material, with means for contracting the ring to abut the sides of the groove.

100 2. An embroidery frame including a hoop having a V-shaped groove in its outer face with a resilient frictional material in the bottom of the groove, in combination with an elastic ring adapted to compress the resilient frictional material, with means for contracting the ring to abut the sides of the groove.

105 3. An embroidery frame including a hoop having a V-shaped groove in its outer face with a recessed channel in the bottom of the groove and a resilient frictional material in the channel, in combination with an elastic ring adapted to compress the resilient frictional material and to abut the sides of the groove.

110 4. An embroidery frame including a hoop having a V-shaped groove in its outer face with a resilient frictional material in the bottom of the groove, in combination with an elastic ring adapted to compress the resilient frictional material and to abut the sides of the groove.

115 5. An embroidery frame including an inner hoop, in combination with a divided elastic outer ring having a cam on one of the di-

vided ends, and a U-shaped lever pivoted to the other divided end and having a screw in its yoke adapted to operate on the cam to clamp the ring around the hoop.

5 6. An embroidery frame including an inner hoop in combination with a divided elastic outer ring having a cam on one of the divided ends, and a lever pivoted to the other divided end and having an abutment adapted to operate on the cam to clamp the ring around the hoop.

7. An embroidery frame including a hoop having a V-shaped groove in its outer face, the sides of the groove being convergingly inclined to the plane of the hoop, and a 15 round-wire ring adapted to be clamped and wedged in the groove between the converging sides thereof.
